UNITED STATES PATENT OFFICE.

ALBERT E. SCHERM, OF CINCINNATI, OHIO.

CROSSING PAVEMENT.

Application filed October 14, 1926. Serial No. 141,632.

The invention relates to a roadway pavement at railroad intersections or crossings to present a smooth and durable surface in a plane with or an unobstructed approach to the tread surface of the rail.

Considerable difficulty has been experienced in providing a suitable and durable pavement construction for railroad crossings on account of the vibration of the rails and ties under the heavy loads of a moving train which soon destroys the pavement so that frequent renewal of the pavement is generally required to keep it in a satisfactory condition. Likewise, the track requires periodical ballasting, necessitating the tearing up of the pavement.

An object of the invention is to provide a pavement consisting of metallic plates or sections for bridging the trackway, the sections fixed to the rails at one or both ends and supported upon the tie at an appropriate distance from the rail.

Other features and advantages of the invention are more fully set forth in the description of the accompanying drawings forming a part of this specification, in which:

Figure 1 is a cross section of the railroad track with the improved crossing pavement applied.

Figure 2 is an enlarged cross section similar to Fig. 1, except showing the same through one of the rails, and with the plates in section.

Figure 3 is a top plan view thereof.

Figure 4 illustrates in cross section a modified form of construction in which plate sheets or slabs are employed for the pavement.

Figure 5 is a top plan view thereof.

Figure 6 is a cross section through a modified form of rail.

Referring to Figures 1 to 3 inclusive of the drawings illustrating the preferred embodiment, 1 indicates the cross ties imbedded in the track ballast 2, and 3 the ordinary T railroad rail spiked to the cross rails. A ledge plate 4 of U form in cross section having the characteristics of the ordinary fish plate, is secured to the web 5 of the rail between the head and base thereof by bolts 6. The plate is provided with an extended offset base flange 7 to lap over the base of the rail to bring its forward or toe end directly upon the cross tie to which it is spiked. A second flange or ledge 8 extends from the

opposite end of the plate for supporting one end of the bridge or pavement plate, with the upper surface of the plate in a plane with the tread surface of the rail, or in approach to the rail so that the rail forms no obstruction in the crossing.

Two types of paving plates are preferably used, one for the outside of the track, and a second for the spacing between the rails which may be termed "intermediate plates." These intermediate plates 9 are preferably of a length to take up the width between the rails, with the opposite ends thereof connecting with the respective rails between which they lie, or connected to the ledge flange of the ledge plate 4. The lower side of each intermediate plate 9 is integrally provided with a rib 10 tapering from the opposite ends of the plate to a base or shoe 11 adapted to rest upon a tie and furnish an intermediate support for the plate. The rib at each of its opposite ends terminates with a transverse rib 12 of the width of the plate, and forms a shoulder against which the edge of the ledge flange may abut. Where the intermediate plates bridge between a pair of rails in the track, the edges of the plate are inclined and spaced from the rail, and therewith form a groove 13 to provide a channel or clearance for the flange of the wheels. The pavement plates are bolted or riveted to the ledge plates and are of appropriate section width which will withstand the heavy vehicle loads to which the roadway may be subjected. In such capacity, a number of plate sections can be readily removed to gain access to the ties or rails, as for instance, at the rail joints, without taking up the entire crossing pavement or materially interfering with the roadway traffic. This also permits plates to be renewed should any become broken.

The outside plates 14, for their end portions which connect with the rail or ledge plates, in structure substantially follow the constructions of the intermediate plates, so that detail reference need not be made. The outside plates preferably are of a length to reach from the rail to the end of the ties, and the outside end thereof preferably is of channel formation as indicated at 15, to provide a base for supporting the plate to the tie, with its upper or face surface in a plane with the tread surface of the head of the rail. It is also provided with a longitudinal intermediate reinforcing rib 16 to

strengthen the plate, as in the case of the intermediate plates.

The end of the roadway pavement adjacent the outside pavement plates 14, is preferably provided with a channel iron nosing 17 slightly spaced from the end of the pavement plate 14, with a pitch or a like filler material 18 intermediate the plate and nosing for furnishing an expansive joint.

10. In the modification shown in Figs. 4 and 5, the pavement plates are represented as of sheet or slab form with plane side supported upon timber shoring 19 resting and secured to the cross ties, and otherwise the 15 structure follows that described for Figs. 1 to 3 inclusive, in the method of securing the plates or slabs to the rail or ledge plates.

Figure 6 discloses a modification of a rail structure in which ledge flanges 20 are formed integral with the rail for supporting the pavement plates and securing the same to the rail in the substitution for the separate ledge plates previously described.

Having described my invention, I claim:

25. 1. A railway roadway crossing pavement, comprising, a ledge plate of channel form adapted to be secured to a rail and engaged between the head and base portions thereof, and a metallic pavement plate or slab secured at one end to the ledge plate and supported upon a cross tie of the rail at a point remote from the rail with the up-

per surface of the pavement plate in plane with the surface of the rail.

2. A railway roadway crossing pavement, 35 comprising, a ledge plate of channel form adapted to be secured to a railroad rail and ties supporting the rail and providing a ledge extension beneath the head of the rail, and a series of metallic pavement plates or 40 slabs secured to the ledge extensions of said ledge plates and supported upon said ties to sustain the plates in plane with the tread surface of the rail.

3. A railway roadway crossing pavement, 45 comprising railroad rails having a ledge extending upon a side thereof, longitudinally therewith, and metallic slab sections fixed to said ledge and having a bearing support upon the rail supporting cross ties.

4. A railway roadway crossing pavement, comprising, railway rails having ledges extending from the opposite sides thereof longitudinally of the rail, a plurality of slab sections arranged and secured in a plane 55 with the roadway and tread surface of the rails, fixed at its opposite ends to the opposing rails of the track and intermediately supported upon the rail supporting cross ties.

In witness whereof, I hereunto subscribe my name.

ALBERT E. SCHERM.
